United States Patent Office.

ABNER S. HARDING AND NICHOLAS REED, OF OTISVILLE, NEW YORK.

Letters Patent No. 63,722, dated April 9, 1867.

IMPROVEMENT IN COMBINATION PADLOCKS.

The Schedule referred to in these Letters Patent and making part of the same.

TO ALL WHOM IT MAY CONCERN:

Be it known that we, ABNER S. HARDING and NICHOLAS REED, of Otisville, in the county of Orange, and State of New York, have invented a new and improved Lock; and we do hereby declare that the following is a full, clear, and exact description thereof which will enable others skilled in the art to make and use the same, reference being had to the accompanying drawings, forming part of this specification, in which—

Figure 1 represents a side elevation of this invention.

Figure 2 is a transverse section of the same taken in the plane indicated by the line x x , fig. 3.

Figure 3 is a longitudinal section of the same, the line y y , fig. 2, indicating the plane of section.

Figure 4 is a detached elevation of the sliding bolt.

Similar letters of reference indicate like parts.

This invention relates to a lock of that class commonly known as commutation locks, the operation of which depends upon the position of a series of disks which are marked on their circumference with letters or figures, and perforated with central holes and radiating slots through which the bolt slides. The bolt is composed of a bar which fits the central holes of the disks, and from which radiate arms which can be made to pass through the radiating slots of the disks, provided said disks are turned to the proper position. The disks are enclosed in a case, one side of which is hinged and fastened by means of a screw which is concealed under the shackle when the device is locked. By removing the screw and opening the hinge, the disks can be removed and the set of the lock changed.

A represents the case of my lock, which is made of brass or any other suitable material. The ends of this case are perforated with holes, a , in which the bolt B slides, and this bolt is provided with a series of radiating arms, b , situated at equal distances apart, and extending from the bolt, so that they enclose an obtuse angle, as shown in fig. 2. On the bolt B, and between the radiating arms b , are mounted the disks C, each of which is provided with a circular cavity, so that the same work close together, and yet leave room for the radiating arms b . Said disks are perforated with radiating slots, c , which correspond in position to the radiating arms, and are of such a size that, by turning said disks to the proper position, the arms b can be made to pass through said slots. On the peripheries of the disks are marked a series of figures or letters, whereby the operation of setting the disks is facilitated, and by interchanging said disks the combination can be changed at pleasure. The case A is provided at one end with a hinged lid, e , which swings on a pivot, f , and is fastened to the body of the case by a screw, g . By removing this screw the lid can be opened, and access can be had to the disks, so as to change the same whenever it may be desired. When the shackle E is locked the screw g is concealed and protected, so that the disks cannot be meddled with by unauthorized persons. If desired, this arrangement can also be applied to door locks or locks of any other construction.

What we claim as new, and desire to secure by Letters Patent, is—

The hinged lid e of the case A, in combination with the screw g , shackle E, disks C, and bolt B, constructed and operating substantially as and for the purpose described.

ABNER S. HARDING,
NICHOLAS REED.
